CIGAR MOLD

Ferdinand Hochherr, Heidelberg, Baden,
GermanyApplication December 9, 1936, Serial No. 114,890
In Germany December 9, 1935.

8 Claims. (Cl. 131—9)

My invention relates to cigar molds, such as are in use in forming or molding the bunches from which the cigar is finally formed.

According to the invention one mold may be used to produce bunches of different shapes and sizes. To this purpose the bottom and cover parts of each bunch mold are built up of a plurality of members adjacent to each other, said members being adapted to be inserted, one or more at a time, in a plate or frame in such manner that by exchanging, adding or taking away one or more members molds may be combined for producing bunches of any desired shape or size in the manner of setting a typographic composition. The connection of the mold members may be effected in any desired manner. According to one embodiment of the invention undercut grooves are provided in base plates of the bottom and cover of the mold and the mold members may have guiding pieces fitting in the said grooves. According to another embodiment the bottom and cover parts of the mold may be made in form of frames in which the individual molds are assembled and secured by suitable fastening members. Preferably the mold members have grooves in their side surfaces and bars are provided fitting into grooves provided in two opposite sides of the frame. The grooves in the sides of the mold members are preferably of semicircular cross section and the connecting bars are of circular cross section fitting into the semicircular grooves of the mold members.

In order to avoid the formation of ridges in the bunches the mold members of the bottom part are formed with excavations or depressions having a bottom of semicircular cross section and perpendicular side walls and the mold members of the cover part are formed with excavations of semicircular cross section of the same diameter as the bottom parts of the excavations in the mold members of the bottom parts. The outer side walls of the cover members are perpendicular and so spaced that the cover member fits snugly into the corresponding bottom member.

The invention is more fully described in the following specification and illustrated in the accompanying drawings, in which:

Figure 1 is a side elevation of the bottom part, partially in cross section through the line I—I of Fig. 2.

Figure 2 is a top plan view of the bottom part.

Figure 3 is a cross section of the cover part taken through the line III—III of Fig. 4.

Figure 4 is a bottom plan view of the cover part,

Figure 5 is a cross section through two corresponding mold members,

Figure 6 is a cross section through the same mold members in molding or pressing position.

Figure 7 is a perspective view of a filling piece, 5

Figure 8 is a top plan view of the bottom part of a second embodiment of the invention,

Figure 9 is a cross section taken through the line IX—IX of Fig. 8,

Figure 10 is a bottom plan view of the cover 10 part of the mold,

Figure 11 is a cross section through the line XI—XI of Fig. 10; and

Figures 12 and 13 are cross sectional views of the mold members of the cover and bottom part 15 respectively.

In the embodiment according to Figs. 1 to 7 the base plate 1 is provided with a plurality of undercut guiding grooves 2 parallel to each other, said grooves being open at one end and closed 20 at the opposite end. The bunch molds proper are composed of a plurality of individual mold members or blocks 3 having on their under surfaces guiding bars 4 fitting into the grooves 2 and in their upper surfaces depressions or recesses 5. 25 The recesses 5 have a semicylindrical or semiconical bottom and their side walls are in the form of perpendicular planes. The mold members for the heads and ends of the bunches are provided with recesses, the bottoms of which are 30 formed according to the desired form of the head or end and the side walls of which are likewise perpendicular. Preferably these end parts have perpendicular slots 6 in their outer ends to allow the tail ends of the bunches to pass 35 through.

The cover plate 7 is also provided with undercut grooves 2' arranged in the same manner and corresponding to the grooves 2 of the bottom plate. The mold members or blocks 3' of the 40 cover plate are provided with guiding bars 4' fitting into the grooves 2'. The recesses 5' are semicylindrical or semiconical and of such width that their perpendicular outer surfaces form sharp edges with the curved inner surfaces of the 45 recesses and the perpendicular outer walls of the cover members will fit exactly between the perpendicular inner walls of the recesses 5 in the bottom members. Accordingly when the cover members are fully inserted into the bottom members a hollow mold of exactly circular cross section is formed as shown in Fig. 6. The cover members for the heads and ends of the bunches may be provided with end openings 6' for the 50 tail ends of the bunches.

The cover plate 7 may be subdivided transversally in order to be adapted to the length of the bunches to be produced. The sections may be provided with positioning pins and holes 8 so that the guiding grooves 2' will be in strict alignment. The sections are secured together by screw bolts 9 and nuts 9'.

For the purpose of assembling the bunch molds first the mold members for the cigar heads are inserted into grooves 2 of the base plate 1. After that intermediate members of the desired form are inserted, one end of one of these intermediate members fitting against the inner end of the head member, and the mold is brought to the desired length by adding further matching members, whereupon a matching end member is adjoined. The grooves are then filled up by filling pieces 10 and the mold members are fastened by a closing bar 11.

20 The cover part of the mold is composed in corresponding manner by first building up the base plate 7 of the cover to the desired length, inserting into the grooves 2' mold members 3' corresponding to and registering with the mold members 3 of the bottom part, and fastening the mold members by a closing bar 11'.

In order to enable the operator to cut off the projecting ends or tails of the bunches the guiding bars of the mold members for the heads and ends are not continued to the ends of the mold blocks but are cut away at a distance from the end surface corresponding to the width of the edge portion of the base plate; however, the end faces of the mold blocks and of the base plate are in alignment.

According to Figures 8 to 13 the base plates 21 and 22 respectively of the bottom and cover parts are made in the form of frames. In the inner surfaces of two opposite sides 23 of these frames corresponding grooves 24 are provided. The mold members 25 have in their side surfaces grooves 26 of preferably semicircular cross section as shown in Figs. 12 and 13. For assembling the molds, the ends of a circular bar 27 fitting into the grooves 26 of the mold members are inserted into the grooves 24 of the frame. Thereupon the mold members for the first bunch mold are inserted into the frame and if required filling pieces are added in order to fill the frame between the sides 23. After that a second bar 27 is inserted into the grooves 24 of the sides of the frame and into the grooves 26 of the mold members of the said first bunch mold. The molds for the other bunches are composed or assembled in the same manner and joined to the first composed mold in such manner that the free half of the bar 27 fits into the adjacent grooves 26 of the second composed mold. After the frame is filled up an end piece or bar 28 is inserted and the molds are secured by screw bolts 29. To secure the mold members in the longitudinal direction of the bunches a rail 31 of U-shaped cross section is provided in one of the grooves 24 and this rail is pressed against the end surfaces of the mold members by screw bolts 30 provided in the corresponding side of the frame.

The cover part of the mold is composed in similar manner. The frames of the bottom part and cover part are provided with suitable positioning means, such as positioning pins and positioning holes (for instance of the same character as those shown at 8 in Fig. 4) in order to secure exact registering of the bottom parts and cover parts of each mold. Suitable connecting

means such as spring latches or the like may be provided in the bottom and cover plates or frames.

The parts are preferably made of metal, for instance light metal alloy to secure durability and light weight. To enable the bunches to dry up in the molds the mold blocks are preferably provided with perforations such as 12. The base plates of the bottom and cover of the mold may also be provided with perforations, for instance between the guiding grooves 2 and 2' respectively.

In using the molds according to the invention a great variety of different bunches may be produced by means of a relatively small number of mold members. Evidently it is possible to assemble molds of different shapes or sizes in one frame.

I claim.

1. A cigar mold having a bottom part and a cover part, each of said parts provided with a plurality of parallel undercut grooves, the grooves in the bottom part registering with the grooves in the cover part, and a plurality of interchangeable mold members adapted to be fixed in said grooves, the mold members in the cover part fitting into the mold members in the bottom part.

2. A cigar mold having a bottom part and a cover part, each of said parts provided with a plurality of parallel undercut grooves, the grooves in the bottom part registering with the grooves in the cover part, a plurality of interchangeable mold members having foot members fitting into said grooves, filling pieces fitting into said grooves, and means to fix said mold members and filling pieces in said grooves.

3. A cigar mold having a bottom part and a cover part, each of said parts comprising a frame, grooves in two opposite sides of said frame, a plurality of interchangeable mold members adapted to be inserted into one of said frames, a plurality of connecting members adapted to hold said mold members in axial alignment in said frames, and means to fix said mold members and connecting members in said frames.

4. A cigar mold consisting of a bottom frame and a cover frame, each of said frames having grooves in two opposite sides, a plurality of interchangeable mold members, the mold members of the cover frame fitting into the mold members of the bottom frame, each mold member having grooves in its side surfaces, a plurality of connecting bars fitting into said grooves, and screw means to fix said mold members and connecting bars in said frames.

5. A cigar mold composed of a bottom part and a cover part, a plurality of mold members each composed of a plurality of removable sections, arranged in tandem fashion on said bottom part and cover part respectively, means for axially aligning the sections of the same mold member in tandem relation, and means for securing the said mold members in position on the bottom part and on the cover part respectively.

6. A cigar mold composed of a bottom part and a cover part, a plurality of mold members each composed of a plurality of removable sections, viz. one section for each end of the mold member and one or more sections fitted between such end sections, means, in engagement with the sections of the same mold member, for aligning said sections longitudinally on the said bottom part or said cover part respectively, and means for securing said mold members in po-

sition on the bottom part and on the cover part respectively.

7. A cigar mold composed of a bottom part and a cover part, each of said parts comprising a body with mold guides, a plurality of mold members each composed of removable sections provided with portions adapted to fit said mold guides and to slide longitudinally thereof in tandem arrangement and axial alignment, and means for securing said mold members in position on the bottom part and on the cover part respectively.

8. A cigar mold composed of a bottom part

and a cover part, each of said parts comprising a body with parallel grooves and with bars the ends of which are adapted to slide in said grooves, a plurality of mold members each composed of a plurality of removable sections arranged in tandem fashion lengthwise of said bars, the sides of said sections engaging said bars and being held thereby in axial alignment, and means for securing said mold members in position on the bottom part and on the cover part respectively. 5

FERDINAND HOCHHERR.
